UNITED STATES PATENT OFFICE.

HAROLD H. NESBITT, OF BELAIR, MARYLAND.

COOLING TANK.

Application filed July 30, 1926. Serial No. 126,059.

This invention relates to improvements in cooling tanks, particularly adapted for use in connection with refrigerating apparatus and the like.

5 An object of this invention is to provide a tank which may be manufactured at a greatly reduced cost over those now in common use.

10 Another object of this invention is to provide a tank having a minimum number of sections easily assembled in such a manner as to materially increase the efficiency, particularly in maintaining a much lower temperature in less operating time for the common 15 pressure unit than is possible in the devices now used in ordinary practice.

Another object of this invention is to provide a tank construction having a main body portion made of a single section of cast metal 20 such as cast bronze or the like, the cooling area and means for facilitating the ice cube freezing being increased by suitably connecting to the main body portion of the tank, tubular sections in open communication therewith.

25 Further objects of this invention will appear in the following detailed description of this device and as disclosed in the single sheet of drawings which is herewith made a part 30 of this application:

In the drawings,

Fig. 1 illustrates an end elevational view 35 of the cooling tank in assembled relationship showing a section broken away in order to disclose the sealing means between the lid or cap and the main body portion of the tank.

Fig. 2 represents a side elevational view of Fig. 1.

Fig. 3 illustrates a plan view of Fig. 2.

40 Numeral 1 designates the main body portion of the cooling tank which may be made of any suitable material such as cast bronze formed into any desirable shape by casting for the purpose set forth. The body portion 45 1 of the tank is adapted to have outwardly extending therefrom along its upper edge, and integrally therewith, a flange portion 2 which is adapted to be brought into sealed relationship with a cap or lid section 3 by means of machine bolts 4 or otherwise. In 50 order to effectively seal the lid and main body portion together, a gasket 5 is positioned between the flange 2 and lid 3. Suitable openings are provided in the lid 3 for receiving fittings connected with the pressure control, intakes for liquid refrigerants, and suction

line; these elements being connected in any suitable manner to the refrigerating apparatus.

In order to increase the cooling area and to facilitate the ice cube freezing, a plurality of tubes are brought into open communication with the main body portion 1 of the tank. These tubes or coils are designated by numeral 6 and are preferably made from copper tubing hermetically sealed or suitably connected to the main body tank portion 1, through openings 9 therein, which may be drilled for receiving the ends of the coils 6. The coils 6 are so arranged in relation to each other as 70 to form suitable receptacles for receiving ice pans 7, the ice pans 7 are supported by means of suitable extensions 8 between the tubular members 6. Absorption coils or tubes 10 are adapted to extend from the sides of the main 75 body portion 1 preferably from a point near the bottom thereof and through openings 11 therein, these openings 11 may be drilled so as to receive the free ends of the coils 10, the ends of the coils 10 being hermetically sealed 80 in any suitable manner to the main body portion 1 through openings 11.

It is preferred in this invention to arrange the cooling tubes and the absorption coils in the relationship disclosed in the drawing, but 85 it is understood that the absorption coils may be located at any desired angle to the main body portion without affecting the merits of this invention, likewise variations and substitutions may be made for the cooling tubes 90 6 disclosed herewith within the scope of this invention.

In order to increase the absorption area a shield or cover 11' for the pans 7 may be located between the cooling tubes 6 and surrounding the pans, thereby forming a shelf 95 closed at the sides for receiving the pans.

This invention provides a cooling tank having an efficiency ordinarily double that of the more common types now in use. The location 100 of the side absorption coils in this invention functions to make it possible to obtain a much lower temperature in less operating time for the compression unit. From the fact that the tank is made from practically a single casting and the lid having in combination therewith absorption tubes, cooling tubes, and pans with their supports, it is apparent that the cost of production is greatly reduced, thereby over the expense of manufacturing a cooling tank of the ordinary type. The tank is made from a minimum number of elements 105 110

in a very simple manner thereby reducing greatly the amount of labor necessary in the manufacture.

What I claim is:

- 5 A cooling tank consisting of a main body portion of suitable metal, the portion having an opening in the top, a lid or cap for the opening, the lid being brought into sealed relationship with the main body portion, absorption coils extending from the sides of the main body portion, the ends of the coils being in open communication with the main body portion of the tank and hermetically sealed thereto, cooling tubes extending from the

main body portion and in open communication therewith, the ends of the tube being hermetically sealed to the main body portion, the cooling tubes being arranged to receive cooling pans therebetween, the pans having suitable supports extending between the tubes, means for increasing the absorption area consisting of a shield made of suitable absorption material adapted to cover the ice pans between the cooling tubes, thereby forming a closed shelf for the pans. 15 20 25

In testimony whereof I affix my signature.

HAROLD H. NESBITT.
